UNITED STATES PATENT OFFICE

JOSEPH H. TEMPLIN, OF PHILADELPHIA, PENNSYLVANIA, ASSIGNEE, BY MESNE ASSIGNMENTS, TO SANTO MANUFACTURING COMPANY, OF PHILADELPHIA, PENNSYLVANIA, A CORPORATION OF DELAWARE.

VACUUM RENOVATING APPARATUS.

1,108,275.

Specification of Letters Patent. Patented Aug. 25, 1914.

Original application filed July 23, 1909, Serial No. 503,969. Divided and this application filed July 23, 1910. Serial No. 573,463.

To all whom it may concern:

Be it known that I, JOSEPH H. TEMPLIN, a citizen of the United States, residing at Philadelphia, in the county of Philadelphia and State of Pennsylvania, have invented certain new and useful Improvements in Vacuum Renovating Apparatus, of which the following is a specification.

My invention relates to improvements in vacuum renovating apparatus in which means for producing a vacuum are employed.

In a prior application filed July 23rd, 1909, Serial Number 503,969, I have shown a system of cleaning wherein a vacuum is employed while in this application which is filed as a division and continuation of said prior application I claim the means shown therein for creating the vacuum.

20 The object of my invention is to produce a vacuum pumping mechanism requiring the least amount of power for driving same, also simple and durable in construction as well as light in weight consistent with its 25 capacity, and furthermore to reduce the vibration to a minimum.

To accomplish the above purpose I have arranged and constructed my apparatus as follows: A main casing supported on a base 30 has an upper or vacuum chamber provided with an inlet and a cover, said inlet being adapted to receive the well known suction hose end. Said vacuum chamber also contains a suitable dust separating device. In 35 the lower portion of the casing is located the vacuum pumping mechanism, the inlet of said pumping mechanism being connected to the vacuum chamber and adapted to exhaust the air therefrom. Means for 40 driving the pumping mechanism are located on a base to which said pumping mechanism and main casing are also secured, the whole thereby forming a compact and truly portable machine.

45 Referring to the drawings in which similar letters of reference indicate like parts, Figure 1 represents a side view of my apparatus partially in section wherein the mechanism is motor-driven, and showing 50 two double-acting pumps. Fig. 2 is a side view of another construction also partially in section wherein one double acting pump is motor-driven. Fig. 3 is a side view, partially in section of my apparatus as con-

structed to be operated by hand. Fig. 4 is 55 a section of a plait shown extended. Fig. 5 is a section of a plait shown compressed. Fig. 6 shows another form of construction wherein a single flexible diaphragm is used instead of the plaited form. 60

In the drawings 1 is the main casing, 2 the vacuum chamber and 3 the cover for same, 4 is the inlet to said chamber adapted to receive the suction hose 5. 6 is a well known renovator attached to the opposite 65 end of said hose 5 and through which the dust-laden air passes into the vacuum chamber, the dust being deposited into the separating device, the purified air passing through the orifice 7 into the inlet 8 of the 70 vacuum producing means.

9 is the base to which the casing 1 is secured. 10 is the frame of the pumping mechanism which is also secured to base 9.

11 and 12 are the inlet and outlet valves, 75 located in their respective chambers in frame 10.

13 is the outlet of chamber 14, said outlet being adapted to receive the end of the well known blowing hose 15. 80

16 are collapsible chambers formed in each side of frame 10. These chambers in my preferable design are formed by bellows shaped plaits 17 secured at their joints by stiffening rings 18 as shown, whereby the 85 plaits 17 retain their form under any conditions of vacuum or pressure to which same may be subjected. The plaits 17 are adapted to be extended or compressed by means of plates 19 which are connected to 90 each other by yoke 20. By means of crank rod 21 one end being pivoted to yoke 20 at 22 the other end being operatively connected to crank pin 23 reciprocating motion is imparted to yoke 20, as shown in Figs. 1 95 and 2 or by means of link 24 connected to yoke 20 by pin 25 and to hand lever 26 by pin 27, said lever being pivoted to bracket 28 by means of pin 29 Fig. 3.

30 is the motor shaft on which crank 31 100 is secured, said shaft receiving its rotary motion from motor 32.

33 is the electric cable attached to the motor and 34 is a plug attached to the free end of the cable and adapted to be attached 105 to the ordinary electric light socket, whereby connection is made to the source of power or driving electric current.

From the foregoing the operation of the mechanism may be readily understood, current being turned on by the operator at the switch causes rotation of the motor shaft and cranks, thereby imparting reciprocating motion to the yokes which alternately compress and extend the plaits or diaphragms thereby causing alternately inrushes of air into the inlet of the pump and through the inlet and outlet valves which operate alternately. The inrushing air into the pump causes an inrush into the renovator, carrying with it any dust to which same may be brought into contact, and depositing same into the separating device, the purified air passing through the pump into the open air or may be utilized for blowing purposes.

It will now be seen that in my construction I reduce the machine to a compact form and reduce the friction of moving parts to a minimum as I have no piston rods or glands nor guide blocks and rods and no possibility of leakage from extra joints of stuffing boxes.

While I have shown my preferable design I do not wish to be limited to the exact details of same as changes may be made by those skilled in the art, which changes may come within the scope of my invention.

Having thus described my invention, what I claim as new and therefore desire to secure by Letters Patent is:—

1. A vacuum pump including in combination, a fixed frame having inlet and outlet ports and valves for closing the same, movable plates, flexible annular diaphragms connecting said movable plates to said fixed frame, said diaphragms being hermetically secured to each other at their inner edges, stiffening rings secured to said inner joints

for clamping the edges of said diaphragms together, and means for reciprocating said plates including a yoke surrounding said frame and secured to said movable plates.

2. A vacuum pump including in combination, a fixed frame having inlet and outlet ports and valves for closing the same, a movable plate, flexible annular diaphragms connecting said movable plate to said fixed frame, said diaphragms being hermetically secured to each other alternately at their inner and outer edges respectively, stiffening rings secured to said inner and outer joints for clamping the edges of said diaphragms together, and means for reciprocating said plate, said reciprocating means including a yoke surrounding the frame and supported by said movable plate.

3. A vacuum pump including in combination a fixed frame having inlet and outlet ports and valves for closing the same, movable plates at each side of the frame, flexible annular diaphragms connecting said movable plates to said fixed frame, said diaphragms being hermetically secured to each other alternately at their inner and outer edges respectively, stiffening rings secured to said inner and outer joints for clamping the edges of said diaphragms together, and means for reciprocating said plates, said reciprocating means including a yoke surrounding the frame and supported by said movable plates.

In testimony whereof I affix my signature in presence of two witnesses.

JOSEPH H. TEMPLIN.
